Atty.

UNITED STATES PATENT OFFICE

WILLIS W. LINDER, OF SALISBURY, NORTH CAROLINA, ASSIGNOR TO THE TERRELL MACHINE COMPANY, OF CHARLOTTE, NORTH CAROLINA, A CORPORATION OF NORTH CAROLINA

BOBBIN-STRIPPING MACHINE

Application filed August 15, 1929. Serial No. 386,117.

The invention has relation to machines of the class used in the textile industry for the purpose of stripping from bobbins residual portions of wound material remaining thereon after substantially all of the contents of the bobbins has been paid off in the processes in which the said contents are utilized. These residual portions must be removed from the bobbins to prepare the latter for further employment. In some cases, residue of rovings are required to be stripped from roving bobbins; in other cases, feeler-waste is required to be stripped from shuttle bobbins. By "feeler-waste" is meant, as usual, the residue of weft or filling still upon a shuttle bobbin when it is expelled from the working shuttle of an automatic weft-replenishing loom in the performance of replenishing operations instituted through the detecting action of a weft or filling feeler.

More particularly, the invention relates to bobbin-stripping machines of the type designed to strip the residue of wound material remaining on a bobbin from the bobbin-barrel by a scraping or wiping action, taking effect in the direction of the length of the bobbin-barrel as a result of relative movement between the bobbin and a stripper-device. In the case of some patented machines a stripper-device is caused to move along a bobbin which for the time being remains in a definite position; in the case of other machines which are in extensive use in practice, a bobbin which is to be stripped is moved lengthwise past a stripper-device. Usually, the relative movement is produced by cam or crank action, in the working of mechanism actuated through the application of power transmitted through a driving band. Machines embodying in their organization mechanism including cams, cranks, and the like, are comparatively expensive to build, require the application of an appreciable amount of power for their actuation, for use require to be located in places where the necessary power-transmission conveniently may be effected, require lubrication, etc., all of which incidents in the nature of drawbacks or disadvantages, restrictions, etc., my present invention obviates.

The invention consists, firstly, in a bobbin-stripper organization characterized by the utilization of fluid-pressure, for instance that of compressed air, for occasioning the relative movement for bobbin-stripping purposes, with substantially direct application of such pressure. It consists, secondly, in novel stripper-devices.

An illustrative embodiment of the invention is shown by the accompanying drawings, in which latter,—

Fig. 1 is a sectional view of the said embodiment showing its features more or less diagrammatically.

Fig. 2 is a plan view of the parts below the dotted line 2, 2, in Fig. 1.

Fig. 3 is a plan view of one of the stripper-members, detached.

Fig. 4 is a view in section on line 4, 4, of Fig. 3.

Fig. 5 is a view showing, on a larger scale than the other views, a feeler-bobbin and a portion of plunger 31 engaged with the tip-end of such bobbin, a small portion of the bobbin-tip being broken away in order to show the inter-engagement.

The machine of the drawings is represented in the latter as employed for stripping feeler-waste from a shuttle bobbin. In certain particulars the machine as shown is adapted for stripping roving bobbins. The adaptation and employment of the machine for stripping residues of roving from roving bobbins taken from the creels of textile machinery after having been substantially depleted of their roving contents will be apparent to those skilled in the art.

In the drawings, a bobbin 1 is in place in the machine, with a stripper-device 2 engaged with the lower portion of the bobbin-barrel below the turns or coils of wound material 3 remaining on the bobbin.

The illustrated machine is organized to occasion the relative movement aforesaid between bobbin and stripper-device by movement of the bobbin bodily endwise with respect to the stripper-device. To the said end, the machine is equipped with a reciprocating bobbin-mover. In different known machines various types and forms of bobbin-

movers are comprised, to many of which the main principle of the present invention is applicable. In this instance the bobbin-mover is exemplified by an endwise-movable plunger 31 that is adapted to push against the bobbin-tip. In this instance, the principle of utilizing fluid-pressure is applied through connecting the said plunger with a piston 41 working in a cylinder 51, such cylinder having in connection therewith provisions for the controlled admission of fluid under pressure at opposite sides, alternately, of the piston. The said provisions include pipes 61, 71, communicating through the opposite heads of the cylinder with the interior-spaces of the cylinder at the opposite sides of the piston. Such provisions include, further, a four-way valve, with the casing 81 of which the said pipes connect. Also, a supply-pipe 91 leading to the valve from a source of fluid under pressure. The means of controlling the application of fluid-pressure to the piston is exemplified by a valve-plug 110 within said valve-casing 81, such valve-plug having a convenient handle 11 by means of which it may be turned, as required for causing the fluid-pressure to take effect against the proper side of the piston to actuate the plunger in the desired direction. At 12 is a discharge-pipe connected with the valve-casing, to lead away the exhaust from the cylinder. The valve-control herein is manual, at the will of an attendant upon the machine, but in the case of embodiment of the invention in a more completely automatic machine, the valve will be controlled and actuated automatically by the mechanism.

With the bobbin properly applied to the machine and engaged with the stripper-device, the fluid-pressure may, through actuation of the valve, be made effective at one side of the piston to move the piston and bobbin-mover to cause the bobbin to travel lengthwise with relation to the stripper so as to be stripped by the latter, after which by proper adjustment of the valve the fluid-pressure may be made effective to return the piston and bobbin-mover to starting position.

As will be apparent, the employment of fluid-pressure means for producing the relative movement between the bobbin and the stripper-device that is required for effecting the stripping of the bobbin obviates the employment of cams, cranks, and other mechanism such as heretofore has been employed for the production of such movement.

It is within the scope of the invention to utilize the fluid-pressure principle of actuation in connection with other modes of producing the movement of a bobbin for the purpose of effecting the stripping thereof; and with mechanism in which the relative movement is attained through travel of a stripper-

device while the bobbin remains in a definite position.

The stripper-device that is employed in a machine in which fluid-pressure is utilized in accordance with my invention may be of any approved specific construction and specific mode of operation. That shown in the drawings and embodying a portion of the invention is of the type comprising a pair of scraper or wiper-blades which are mounted in the machine with capacity for movement toward and from each other, so that they may be opened by being spread apart to receive between them the barrel of a bobbin which is to be stripped, and may be closed together upon the said barrel to ensure scraping or wiping off the residual wound material in a stripping operation. In this instance, the blades 21, 21, are attached to carriers 4, 4, and the required movability of the blades is provided for by such carriers being pivoted at 5, 5, to a bed 6. For the convenient actuation of the blades for closing and opening, each carrier is connected by a link 7 to an operating lever 8 that is pivoted at 9 upon the bed. The said bed has a hole 10 therethrough, situated intermediately with respect to the blades 21, 21, and designed to accommodate the bobbin operated upon. Through such hole the leading portion of the bobbin is projected as the bobbin is thrust through between the blades 21, 21, by the working stroke of plunger 31. One carrier and its blade are located at one side relative to the said hole; the other carrier and its blade are located at the other side relative to the hole. In virtue of the link 7 which connects one blade-carrier 4 with the operating lever 8 being engaged with an arm of such lever at one side of fulcrum 9 of the lever, while the link connecting the other blade-carrier with the lever is engaged with the lever at the other side of the said fulcrum, movement of the lever will impart movement to both blade-carriers simultaneously but in opposite directions relative to each other. Thus, through movements of the lever 8, simultaneous movement of the blades toward each other for closing them upon the bobbin which is to be stripped is produced, and subsequent simultaneous movement away from each other for opening them apart. In the present instance, the lever 8 is hand-operated. In a more completely automatic machine provision will be made for operating it automatically. In order to attain what may be termed parallelism of the acting edges of the blades 21, 21, and a parallel-motion movement of the blades as they open and close, I have located the pivot 5 of one blade-carrier 4 at one end of such blade-carrier and connected the actuating link 7 to the free opposite end of such blade-carrier, and have located the pivot of the second blade-carrier at the other end of the latter and connected the other link 7 to the free end of said second

blade-carrier. Thereby, as will be apparent from Fig. 2, as the blades are closed together upon a bobbin the concavities 22 which are formed in the acting edges of the blades are caused to fit against symmetrically-disposed opposing segments of the bobbin-periphery.

Constructional details of mechanical embodiments utilizing fluid-pressure for the purposes herein set forth may vary in many respects.

In the case of the illustrated embodiment provision is made for arrest of the plunger and piston at the end of the stroke thereof in each direction by means of a hole through 15 the piston from top to bottom, and a valve-member 32 seating around said hole at the upper side of the piston, with a valve-stem 33 extended down through the said hole and receiving upon its extension below the piston 20 and expanding spiral spring 34 confined between the under side of the piston and a foot 35 at the lower end of the valve-stem. The said spring acts with a tendency to press the valve against the said seat, so as to keep the 25 hole through the piston closed. As the piston completes its down-stroke occasioned by the fluid-pressure acting against the top surface of the piston, the foot 35 of the valve-stem encounters the closed lower end of the cylinder, with the result that the valve is separated 30 from its seat so as to permit fluid-pressure-medium to pass through the hole in the piston, from the upper side of the latter to the lower side, thereby equalizing the pressure at both 35 of the sides of the piston, so that the down-stroke is arrested with a cushioned effect, and the piston and plunger remain at rest at the conclusion of their working stroke.

The screw-threaded upper end of the 40 plunger 31 extends through the piston 41 and receives upon its upwardly projecting extremity a nut 36. In the upstroke of the piston and plunger in returning toward the normal or starting position thereof, this nut 45 encounters the upper head of the cylinder, arresting the piston and plunger, whereupon the fluid-pressure at the under side of the piston, through acting against the foot 35 of the valve-stem, operates to raise the valve 50 from its seat, this raising permitting flow of the fluid-pressure-medium through the hole in the piston, from below the piston into the space above the piston, thereby equalizing the fluid-pressure below and above the piston 55 and cushioning the arrest of the piston.

What is claimed as the invention is:—

1. In a bobbin-stripper machine, the combination with a bobbin-stripper device, and a bobbin-engaging device, of fluid-pressure actuated means whereby relative movement between the bobbin and the stripper-device is yieldingly produced and the stripping thereby effectuated.

2. In a bobbin-stripper machine, the combination according to claim 1, characterized

by the employment of a cylinder, a piston from which the relative movement required to produce the stripping action is transmitted, conduits for the pressure-medium in communication with the cylinder at opposite sides of the piston, and a valve-device selectively controlling the flow of said pressure-medium through the said conduits.

3. In a bobbin-stripper machine, a stripper-device comprising a pair of stripper-members having bobbin-receiving concavities in their proximate edges, with said members in parallelism longitudinally and respectively pivoted at opposite ends, an actuating lever, and links connecting the free ends of the respective stripper-members with the said lever at opposite sides of the lever-fulcrum, whereby through movement of the lever said members are brought closer together or separated with parallel motion.

4. In a bobbin-stripping machine, the combination with a bobbin-stripper device of a fluid-pressure-actuated plunger, and means for relieving the fluid-pressure at each end of the movement of the plunger.

5. In a bobbin-stripping machine, the combination with a bobbin-stripper device of a plunger operated by a fluid-pressure-actuated piston, and means for relieving the fluid-pressure against the piston at each end of the stroke of the latter.
